STEEL DOOR CONSTRUCTION

Cecil Schofield, Lakewood, Ohio, assignor to Republic Steel Corporation, Cleveland, Ohio, a corporation of New Jersey

Application January 17, 1951, Serial No. 206,443

2 Claims. (Cl. 189—46)

The present invention relates generally to the art of making doors and is more particularly concerned with novel fabricated metal doors.

Among the more serious problems facing those skilled in the art of making doors of metal and especially fabricated metal doors, are the over-size and over-weight of the doors and the high cost of their manufacture due to the large number of operations involved in making and assembling the separate parts; and the complexity, number and variety of dies required to make these separate parts. One important difficulty concerns the manner of attachment of the two main door parts so that the resulting doors are not too thick and bulky and yet are open sufficiently through their midsections during the assembling operation so that securing means therefor can be located and fixed in place readily and rapidly. Another related difficulty pertains to the insulating and cushioning of metal doors in order to reduce, insofar as possible, shock transfer between two main body portions of the door. Despite the customary bulk and thickness of such fabricated doors the problem of providing insulating and cushioning means has not heretofore been satisfactorily solved and as a result such desirable means are not normally provided.

In accordance with my invention, the various shortcomings, difficulties and disadvantages of the prior art, including those set out above, can be overcome and additional advantages can, at the same time, be obtained. Moreover, these novel results can be gained without incurring any economic disadvantage either from the standpoint of manufacture, installation or maintenance of these doors.

Those skilled in the art will gain a further understanding of the present invention and further appreciation of the importance of its contribution to the art upon consideration of the following detailed description, reference being had to the drawings accompanying and forming a part of the specification, in which:

Fig. 1 is a side elevational view of a fabricated metal door of this invention, parts being broken away in the interest of clarity;

Fig. 2 is a fragmentary, top plan view of the door of Fig. 1;

Fig. 3 is a fragmentary, sectional view taken on line 3—3 of Fig. 1;

Fig. 4 is a fragmentary, vertical, sectional view of the door of Fig. 1 taken on line 4—4 thereof;

Fig. 5 is a fragmentary, perspective view of an upper rib of the said Fig. 1 door and a tie bar assembled with said rib;

Fig. 6 is an enlarged fragmentary view of the door of Fig. 1, indicating the structure and arrangement of latch-supporting elements within said door;

Fig. 7 is a fragmentary, elevational view of an edge portion of the Fig. 1 door, showing an opening therein through which portions of the latch mechanism may project;

Fig. 8 is a perspective view of an element of the supporting structure for the latch mechanism of the Fig. 1 door; and,

Fig. 9 is a fragmentary, vertical, sectional view of a portion of the door of Fig. 1, taken on line 9—9 of Fig. 6, through the latch-supporting portion of the door.

Generally, a door embodying this invention comprises spaced front and back panels, a plurality of ribs secured to the inner side of the front panel and provided with transverse openings, a plurality of ribs secured to the

2

inner side of the back panel but offset relative to the front panel ribs and substantially paralleling them and having transverse openings for registry with the openings in said front panel ribs, and means including tie bars to be disposed between the panels and to extend through the registered openings of the ribs and tie the ribs together and hold the panels in position with respect to each other.

More specifically, and with particular regard to the drawings, a typical door D of this invention comprises a generally channel-shaped, rectangular, sheet metal, front panel 10 having inwardly directed relatively short flanges 11 extending substantially the full length of the element on one side and extending along the other side from points adjacent to the top and bottom of the panel to spaced points in an intermediate portion of said panel. A second, or back panel 13, suitably of the same shape and dimensions as panel 10, is provided for cooperation with panel 10 to define the sides and edges of the door structure, flanges 14 opposing and being spaced closely to corresponding flanges 11 when the panels are assembled together. Panels 10 and 13 are secured together at spaced points along their edges by means of tack welds 15 between said opposed flanges 11 and 14. Flanges 11 and 14 and sides of panels 10 and 13 are partially cut away on one side to define an opening 17 in the edge of door D to accommodate portions of a suitable latch mechanism, which forms no part of this invention and is accordingly not illustrated. Panels 10 and 13 are further provided with registered apertures 18 adjacent to said cut-away side portions to receive parts of said latch mechanism.

A plurality of generally channel-shaped ribs 20 having relatively short flanges 21 extending outwardly from flaring channel sides 22 are secured to the inner sides of the panels 10, flanges 21 bearing against the panels and suitably being spot welded thereto at a number of spaced points. Ribs 20 are so dimensioned lengthwise that they do not extend completely from edge to edge of the panels but terminate adjacent the opposite edges thereof and short of the sides of the panels. These ribs are furthermore disposed substantially parallel to the top and bottom edges of panels 10 and 13 and are provided near their ends with transverse registered apertures 24 in their sides in which to receive securing means by which attachment of the front and back panels may be made, as will be described. The ribs of panel 13 are offset relative to those of panel 10 to permit assembly of the front and back panels with apertures 24 in register, the ribs of the two panels, however, being relatively closely spaced in four spaced groups, as shown in Fig. 1, to provide maximum strength and stability in the resulting door structure.

A plurality of sheets 26 of flexible, non-metallic insulating material, specifically heavy corrugated paper, are glued to the inner surface portions of the panels 10 and 13. These sheets of paper are arranged in such a manner that when these panels are assembled together, as shown in Fig. 4, the webs of ribs 20 bear against portions of these sheets and the ribs therefore do not come directly into contact with the opposing panel elements in any instance. Felt or other insulating materials of commerce, may be substituted for this corrugated paper for this purpose, as those skilled in the art will understand.

Two tie bars 30 are employed to secure panels 10 and 13 in assembled relation, said bars extending vertically of the door through registered apertures 24 and having end portions normally disposed above the uppermost and below the lowermost ribs 20. These bars 30 are generally channel-shaped and they have upper ends formed with tongues 31 which are bent to a flat or open position to engage the upper side of the upper rib of the panel assembly, as shown in Fig. 5, whereby the tie bars are retained in position against gravity when the door is in upright position. The lower ends of the tie bars are each fitted with a channel-shaped cap 33 which is tack welded to its bar 30 so that these bars may be retained in place in the event that door D is inverted.

The upper end of door D is closed by a channel-shaped

cap 35 having closed ends and spot welded in place with its side and end portions in engagement with the upper side and edge portions of panels 10 and 13. Cap 35 is provided with two spaced transverse apertures 37 in its web portion and with nuts 38 which are welded to the under side of the said web in register with openings 37. Nuts 38 may receive and engage threaded ends of hanger rods which in turn may be suspended from wheels on an overhead track whereby door D may slide edgewise in the customary manner, this auxiliary structure being illustrated in outline in Fig. 1.

The lower end of the door may similarly be closed by means of a channel-shaped floor 40 having an open and a closed end and being secured in place in the lower portion of said door by means of spot welds between the sides and closed end of floor 40 and the lower side portions and edge portion of panels 10 and 13. By providing floor 40 with an open end, this element may receive and engage stationary guide and stop means (not shown) to control the motion of a door to some extent and prevent derailment of its suspension means.

The supporting structures for the latch mechanisms comprise a group of four elements arranged around openings 17 and 18. The structures include two pairs of angle irons 45 spot welded to the inner sides of panels 10 and 13 adjacent to the upper and lower edges of openings 18. A pair of channels 47 are similarly secured with their edges opposed to panels 10 and 13 adjacent to the side edges of openings 18. One of the channels 47 has a window 48 (Fig. 8) in their web portions for registry with openings 17. Thus, channel elements 47 and angle irons 45 cooperate, as indicated in Figs. 6 and 9, to provide a compartment within the door to receive the latch mechanism.

Having thus described the present invention so that those skilled in the art will be able to gain a better understanding and practice the same, I state that what I desire to secure by Letters Patent is defined in what is claimed.

What is claimed is:

1. A light-weight, sound-insulated and cushioned, fabricated metal door comprising flanged front and back sheet metal panels joined together along their edges and defining a hollow shell, support means in the shell for the panels comprising a plurality of generally channel-shaped ribs welded to the inner side of the front panel and extending toward and having webs disposed adjacent to the rear panel and a plurality of generally channel-

shaped ribs welded to the inner side of the back panel and extending toward and having webs disposed adjacent to the front panel, and sound-insulating and cushioning means in the shell comprising sheets of flexible non-metallic material attached to the inside surfaces of the front and back panels between the ribs carried by said panels, respectively, each rib web engaging one of said sheets and all said rib webs being spaced from opposing portions of said panels by said sheets.

5 2. A light-weight, sound-insulated and cushioned, fabricated metal door comprising flanged front and back sheet metal panels joined together along their edges and defining a hollow shell, support means in the shell for the panels comprising a plurality of generally channel-shaped ribs welded to the inner side of the front panel and extending toward and having webs disposed adjacent to the rear panel and a plurality of generally channel-shaped ribs welded to the inner side of the back panel and extending toward and having webs disposed adjacent to the front panel, said ribs being arranged in a plurality of pairs spaced apart longitudinally of the door, each pair consisting of a rib connected to the front panel and a rib connected to the rear panel, and sound-insulating and cushioning means in the shell comprising sheets of flexible non-metallic material attached to the inside surfaces of the front and back panels between the ribs carried by said panels, respectively, each rib web engaging one of said sheets and all said rib webs being spaced from opposing portions of said panels by said sheets.
